UNITED STATES PATENT OFFICE.

JOHN F. DUKE, OF LONDON, ENGLAND.

DESIGN FOR A FLAG OR BANNER.

SPECIFICATION forming part of Design No. 29,052, dated July 19, 1898.

Application filed June 1, 1898. Serial No. 682,297. Term of patent 7 years.

To all whom it may concern:

Be it known that I, JOHN FREDERICK DUKE, a subject of the Queen of Great Britain, residing at London, England, have invented and 5 produced a new and original Design for Flags or Banners, of which the following is a specification, reference being had to the accompanying drawing, forming part thereof.

The drawing is a face view of my design.

10 As shown in the drawing, the leading or material feature of my design consists of the representation of part of the national flag of the United States of America with a part of the "Union Jack" of Great Britain. The 15 diagonal from *a* to *b* on the drawing divides said parts and constitutes, in fact, their line of meeting or contact, the portions above said line representing one-half of the United States flag and the portions below said line representing one-half of the Union Jack. *c* represents the blue portion of the United States flag, and *d d* the stars on said portion. *e e* represent the red stripes, and *f f* the white stripes on same flag. *g g* represent the red 25 portions, *h h* the white portions, and *i i* the

blue portions of the Union Jack. *k* represents the American eagle placed across said diagonal or meeting line *a b*. *l* is a heraldic lion also placed across said meeting line. The lion has one paw resting on a shield *m*, 30 which bears pictorial representations of a rose, a thistle, and a shamrock. The waving lines *n*, which extend along part of said meeting lines *a b*, represent the Atlantic ocean, and *p p* are hands shown as meeting each other 35 across said ocean. The lines *n* will generally be colored blue.

Having described my invention, what I claim as new, and desire to secure by Letters Patent, is—

The design for a flag or banner as herein shown and described.

In witness whereof I have hereunto signed my name in the presence of two subscribing witnesses.

JOHN F. DUKE.

Witnesses:

GEORGE C. BACON,
ROBERT M. SPEARPOINT.
